ICE SPUD

Nikolajs J. Bundze, Hazel Park, Mich.

Application March 24, 1955, Serial No. 35,184

Term of patent 14 years

(Cl. D54—13)

Figure 1 is a side elevational view of an ice spud showing my new design;

Figure 2 is a fragmentary top plan view thereof;

Figure 3 is a fragmentary bottom plan view;

Fig. 4 is a cross-sectional view taken on the line 4—4 of Fig. 1; and

Fig. 5 is a cross-sectional view taken on the line 5—5 of Fig. 2.

The characteristic features of my new design reside in the portions shown in solid lines.

I claim:

The ornamental design for an ice spud, as shown and described.
